UNITED STATES PATENT OFFICE.

CHARLES H. LYNCH AND EDWARD T. BOYLAN, OF BROOKLYN, NEW YORK.

CAR SEAL.

Application filed May 22, 1922. Serial No. 562,588.

To all whom it may concern:

Be it known that we, CHARLES H. LYNCH and EDWARD T. BOYLAN, citizens of the United States, and residents of Brooklyn, in the county of Kings and State of New York, have invented certain new and useful Improvements in Car Seals, of which the following is a specification.

This invention relates to car seals.

10 In the transportation of freight by railroad it has been found necessary to affix in addition to the freight car door locks, a seal to indicate in case the seal is broken that the contents have been tampered with. As the 15 freight car train passes from one division of the railroad to another or from one railroad line to another the seals are inspected in order to see that they are intact and in case they are broken the particular division on 20 which the tampering took place is located. If, however, the seal can be unfastened without its destruction then the inspection is useless and it is impossible to determine when and where the goods were stolen in 25 case of theft.

One of the objects of this invention is to provide a car seal that cannot be unfastened without destroying the seal so that on the usual inspection it would be disclosed that 30 the seal had been tampered with. Another object of this invention is to have means to indicate when the seal is locked. Still another object is to provide a seal that will be economical to manufacture and one that will 35 be easily applied.

Referring to the drawings:—

Figure 1 is a view in elevation of a freight car seal embodying the principles of my invention before it is secured to the freight 40 car.

Figure 2 is a view in elevation of a freight car seal in locked position.

Figure 3 is a longitudinal, sectional view 45 showing the metallic strap partially in elevation and part broken off and partially inserted in block.

Figure 4 is a longitudinal, sectional view showing the metallic strap in locked position.

50 Figure 5 is a detail longitudinal, sectional view of the seal block.

Figure 6 is a detail cross sectional view of the block.

55 Figure 7 is a detail view of the metal strap blanked out and prior to assembly.

In carrying out my invention I propose

to make the car seal in two parts and for that purpose I provide a die formed metallic block and a metal strap.

The metal strap 1 is blanked out, see Fig. 60 ure 7, with a rectangular piece 2 of greater width than the remainder of strap 1 at one end and at the other end and adjacent thereto is a rectangular hole 5. Near the rectangular piece 2 in strap 1, two tongues 3 65 and 4 are pushed out of strap 1. The rectangular end piece 2 is bent through an angle of 90° to the strap 1 prior to assembly. See Figures 3 and 4, and tongue 3 is bent out while tongue 4 is bent back to overlap 70 tongue 3.

Strap 1 is inserted in block 6 through the base thereof and pulled through block 6 and out of opening 10 in the top of the block. It is then pulled through until the rectangular bent over end piece 2 of strap 1 bears against the shoulder 11 of chamber 9 in block 6. The end piece 2 of strap 1 having been first dipped in acid, the block is then turned around and chamber 9 is treated with 75 acid and molten metal is run therein to completely fill chamber 9 and holes 12, 12' in the walls of block 6. The purpose of holes 12, 12' is to provide means to prevent the extraction of the metal plug. With reference 80 to Figure 5, it will be seen that metal block 6 has a chamber therethrough divisible into three sections. The top section 7 has one side thereof sloping at about a 60° angle 85 opening into section 8 which is a rectangular chamber and which in turn opens into a wider rectangular chamber 9. The function 90 of the sloping wall in the top section is to guide the end of strap 1 into locking relation with the tongues 3 and 4 as well as to enable the block 6 to have as small an opening 10 as possible. Opening 10 is held closely to size and is slightly larger than the double thickness of strap 1. It is only 95 sufficiently large to enable strap 1 when 100 doubled back on itself to be inserted easily therein.

The operation of the device is as follows:

After the serial number is stamped in the soft metal strap 1, the strap is fastened 105 around the lock or fastenings of the freight car door in the usual manner and the loose end is pushed down into opening 10 where the sloping wall of section 7 and straight wall of section 8 guide the end of the strap 110 to 1 in such a fashion as to cause tongue 4 to snap into opening 5. A slight pull on strap

1 will then cause strap 1 to travel up against tongue 4 and over, and then under tongue 3, in which position strap 1 becomes locked and cannot be withdrawn without either 5 breaking strap 1 or wedge 6 since any movements of strap 1 will merely cause it to bear against either tongue 3 or tongue 4.

Hole 5 in strap 1 is of sufficient length so that a portion of it is visible until it 10 snaps over tongue 4 in order that the operator of the seal has a positive indication that the free end of strap 1 has been inserted a sufficient distance to be securely locked.

It will thus be seen that I provide a 15 simple device cheap to manufacture and one that cannot be tampered with without destroying the seal. Of course the device might be made use of for other purposes besides that of sealing freight cars, such as for 20 sealing trunks in warehouses.

What we claim is:

1. A seal comprising a metal strap and a metal block, said strap terminating at one end in a rectangular end piece to prevent 25 withdrawal and overlapping and opposed tongues adjacent said rectangular end piece, said tongues being integral with said strap for locking the other end of said strap in said block.

30 2. A seal comprising a metal strap and a metal block chambered throughout its length, said strap terminating at one end in a rectangular end piece of greater width than the strap and bent back to divide the 35 chambered block into two compartments, a plug to fill one of said compartments, and means to prevent withdrawal of the plug.

3. A seal comprising a metal strap and a metal block chambered through its length, 40 said strap terminating at one end in a rectangular end piece bent over to divide the chambered block into an upper and lower chamber, shoulders in said chambered block for said end piece to bear against, said walls

having holes therein from said lower chamber, said lower chamber and holes filled by a plug. 45

4. A seal comprising a metal strap and a metal block, said metal strap having a rectangular end piece at one end of greater 50 width than the strap, tongues in said strap adjacent to the rectangular end piece, one of said tongues overlapping the other, a chamber in said block, means to prevent withdrawal of the rectangular end piece of 55 said strap, the walls of said chamber adapted to guide the other end of said strap containing a hole into locking relationship with the aforesaid tongues.

5. A seal comprising a metal strap, a 60 metal block and a plug, said metal block having two internal communicating chambers, one of said chambers being wider than the other and having ports in the side walls thereof for the plug when molten to fill and 65 solidify in, and a rectangular end piece integral with said strap to fit the wider chamber and close communications between the two chambers to prevent the plug when molten filling the two chambers. 70

6. A seal comprising a metal strap and a metal block said strap terminating at one end in a rectangular end piece and having a hole 75 therein adjacent the other end, opposed and overlapping tongues carried by said strap adjacent the rectangular end piece, chambers in said block, said end piece adapted to close communications between said chambers, one of said chambers having a wall sloping for 80 a portion of its length and then parallel to the opposite wall to guide the end of the strap with the hole in it into locking relationship with the tongues.

Signed at New York in the county of New 85 York and State of New York this 13th day of May A. D. 1922.

CHARLES H. LYNCH.
EDWARD T. BOYLAN.
